UNITED STATES PATENT OFFICE.

CAREY W. THOMPSON, OF NEW YORK, N. Y., AND HENRY C. BEELER, OF DENVER,
COLORADO.

PROCESS OF TREATING HYDROCARBONS.

Application filed September 29, 1921. Serial No. 504,247.

To all whom it may concern:

Be it known that we, CAREY W. THOMPSON and HENRY C. BEELER, citizens of the United States, and residents of New York city, New York, and Denver, Colorado, respectively, have invented certain new and useful Improvements in Processes of Treating Hydrocarbons, of which the following is a specification.

10 Our present invention relates to an improved method of treatment of hydrocarbon oil or vapors to increase the saturation of the resulting oils, and the invention includes the novel process hereinafter more fully described and particularly defined by the appended claim.

In the following description we explain our invention by reference to the accompanying drawing in which—

20 The figure is a longitudinal section through the converter.

Referring by reference characters to this drawing the numeral 1 designates a suitable hopper designed to contain a pulverulent or granular carbon containing material such as spent shale, (or oil bearing shale from which the oil has been driven off) which we have found an excellent material for our purpose, though other carbon containing material may be used, or a material such as sand, gravel or other inert material may be used to start as it soon accumulates carbon. This material acts to distribute the heat evenly through the oil together with the stirring action of the screw as hereinafter described, preventing the incrustation of carbon on the shell of the still or converter. This hopper delivers the material through connection 1^a to a converter chamber 2 which is in the form of a series of stills joined

30 together and set horizontally or on a suitable incline as may be desired for treatment of different hydrocarbon bodies, as for example, in case of vapors the horizontal form would be best, while with oils a slight incline would be preferable. These combined stills or converters can be constructed of any diameter or length, about 3 feet diameter by 40 feet long would be a practical design.

40 Within this works a conveyor screw 3 driven continuously by any suitable means so that there is a progressive feed of the material from the hopper to the discharge 2^a which communicates with seal conveyor 4

from which the material may be continuously removed by elevator 5 to bin 6, or may be returned to hopper 1 for reuse.

55 The converter chamber is enclosed in a heat chamber 7 as shown, which may be supplied with heating products or gases through pipe or conduit 8 from any suitable source, (not shown). On the upper side of the converter 2 are the vapor chambers 9, 10 and 11, which are representative of any desired number, the converter chamber above the screw being open at these points to allow free escape of the vapors generated into the vapor chambers from the substance treated.

60 The chamber 9 is connected by a pipe 9^a with any desired apparatus such as a super-heater or condenser (none of which is shown), while the chambers 10 and 11 communicate by ports or passages 10^a, 10^b and 11^a with a common chamber 13 which extends back to and communicates with a chamber 13^a near the initial end of the conveyor which chamber 13^a is in communication with the interior of the cylinder.

65 The initial end of chamber 13 may be provided with an outlet as by pipe 13^b. Spent shale or other carbon bearing material or gravel is supplied to the initial end of the converter from the hopper 1 as above described and hydrocarbon vapors or crude oil to be treated is supplied from any suitable source (not shown) through pipe 14. The portion of the converter to which the shale or gravel and oil or vapors are supplied constitutes a cold chamber, and if vapors are supplied through pipe 14 they 70 condense on the cold material used, or crude oil when treated mixes with the material used.

75 The material with the oil or condensed vapor is moved by the conveyor screw progressively towards the discharge end, and hence into successively hotter zones. In entering the zone of chamber 9 the first or lightest vapors are driven off in said chamber and thence through pipe 9^a to any desired apparatus as stated, the temperature at this point being, for example 500° F. On reaching the zone of the first half of chamber 10 for example a temperature of say 600° F. is encountered and a further vaporization takes place, the vapors passing out through passage 10^a into chamber 13, as also do the vapors generated in the 700° F. zone

through passage 10^b. The final or hottest zone, say 900° F., is reached in chamber 11, when the remaining oil is vaporized and passed through passage 11^a into the end of chamber 13 from which they may be withdrawn if desired for special treatment through pipe 13^b.

The vapors rising into chamber 13 from the several vapor chambers travel towards 10 the initial end whence the lighter vapors pass by way of pipe 13^b to the superheater or condenser system as desired, while the heavier vapors condense in the cold chamber 13^a and drop on the carbonaceous or gravel 15 or like material and are again passed through the converter.

We have found that if superheated steam or fixed gas is introduced into the vaporization chambers this facilitates vaporization 20 and is an aid in the saturation process.

This may be accomplished by pipes 16 or 16^a connected to any suitable source of steam supply (not shown).

It will be understood that the vapors

treated and saturated according to our process may be subsequently fractionated in any desired manner.

Having thus described our invention, what we claim is:

A process of converting hydrocarbons, 30 which includes the step of commingling a body of hydrocarbon with a moving body of gravel, subjecting said material at atmospheric pressure to heat, independently removing the lightest fractions from the retort, and successively removing the heavier fractions from the body of the mixture undergoing distillation at successive zones of increasing temperature, commingling said vapors within the vapor space of the 40 retort and returning the fraction condensed within the region of the vapor take-off in the vapor space to the gravel before said gravel reaches the zone of heat treatment.

In testimony whereof, we affix our signatures.

CAREY W. THOMPSON.
HENRY C. BEELER.
